**APPARATUS FOR MAKING CONCRETE
BUILDING SEGMENTS**

Albert Henderson, Pittsburgh, Pa.

Application January 9, 1957, Serial No. 633,267

7 Claims. (Cl. 25—131)

This invention pertains to apparatus for making pre-cast reinforced concrete segments such as those described and claimed in my co-pending U. S. A. application Ser. No. 626,448 filed December 5, 1956.

My invention has for one of its objects the provision of a simplified mold arrangement and molding process for making the segments with various desired vertical wall and partition spacings in a simplified and improved manner, and wherein the floor and roof slabs may be poured simultaneously with and formed integrally with vertical walls, and without the necessity of providing separate mold sides for segments of various widths and wall spacing.

Another object of my invention is to provide vertical mold walls that can readily be adjusted relative to one another on horizontal mold walls, to form vertical walls of various spacings, it being possible to use the same vertical and horizontal mold wall members for the upper half as for the lower half of a building segment of the type shown in my said application.

In the accompany drawing,

Figure 1 is a vertical sectional view through a casting assembly that embodies my invention;

Fig. 2 is a cross sectional view thereof;

Fig. 3 is a plan view thereof, and

Fig. 4 shows a manner in which the mold members of Fig. 1, and particularly the bottom mold members may be positioned to form a gabled roof for that portion of a segment which will serve as the top or roof therefor.

Fig. 5 is a plan view showing a modification of Fig. 3.

Beams 2 and foundations 3 are provided for supporting the mold bottoms 4. The beams and mold bottoms may be made in successive lengths so as to permit the casting simultaneously of a plurality of segments. Bracing angles 5 are secured to the beams 2 and also support the mold bottom plates 4.

Mold side walls 6 are supported by the beams 2 as shown more clearly in Fig. 2, to form the bottom slab-like bottom 9 which will have to be filled in at various areas between the vertical molds having vertical walls 7—7 and 8—8 respectively. Mold blocks 10 serve as end mold walls for the ends of the slab-like members 9.

In order to provide for desired vertical wall spacing, the side forms 6 have holes 11 suitably of 1-inch spacing, to receive bolts 12a that extend through angles 12 which are formed unitarily with the vertical mold walls. The holes through the angles 12 are elongated so as to permit some adjustment of the vertical mold walls relative to the bolts 12a, to distances less than the 1-inch spacing of the holes in the side forms.

Steam pipes 13 may be provided for hastening the curing of the concrete.

Plates 15 will be hingedly or flexibly connected to the various vertical walls, and bolted down as at 15a, to prevent bulging up of the concrete from the slab at those areas, during filling of the vertical molds.

When it is desired to smooth the concrete after pouring of the slab, the plates 15 will be held up by a chain

2

16. A turnbuckle arrangement at 17 will serve to hold the mold walls vertical, one of these adjustable braces being provided for each vertical mold at each end.

In Fig. 4, I show an arrangement for giving a gable roof form to the half segment that will be inverted and placed upon the segment of Fig. 1, although of course, this roof or ceiling can be flat. However, when it is desired to have a pitched or gabled form, the adjacent ends of the beams 2 will be lowered a desired distance determined by the spacing members 18.

The segments that are respectively formed by the upper and lower sections will be assembled end-to-end to form a complete building; the walls of each segment being in longitudinal alignment with the walls of adjacent segments. Partitions crosswise of the said vertical walls will be inserted at suitable distances, to form closed rooms of desired length, and door and window openings provided, as described in my said application.

Referring now to Fig. 5, I show in plan view, a modification wherein the mold sides for forming the vertical walls or partition are adjustable along the bottom mold wall and its side forms, to vary the thickness of the vertical walls, instead of forming such walls of fixed thickness as provided for by the mold walls 7—7 and 8—8.

25 To this end, I make the mold walls for each partition or other vertical wall of L-shape. Each mold half has a leg 20 and a leg 21 that are formed unitarily with each other, to form a box-like cavity. Each of these half-mold members has an extension 12b at its lower edge, to receive bolts 12a, for adjustment along side forms as in the case of Fig. 3.

The short legs of these half mold members have perforations 22 and they are overlaid by lips 23 secured to the upper edges of the legs 20. When the members 20 are moved toward and away from one another, the lips 23 will slide along the upper edges of the respective legs 21 and bolts or pins will be dropped through the lips 23 into the holes 22.

The holes 22 have the same spacing as the holes 11 40 in the walls 6 of the bottom mold or trough.

Reinforcing steel as indicated in dash lines, Fig. 1, will be positioned in the bottom wall mold and bent up into the vertical wall cavities. The reinforcing steel will, therefore, become imbedded when the vertical and bottom mold cavities are filled.

45 In order to make cantilever extensions integrally with the castings, as shown in my said co-pending application, the end blocks 10 can be moved in the trough or bottom mold away from the vertical mold walls 7, the length of the extension depending, of course, upon the distance the blocks 10 are moved.

Cantilever projections of the slab-like portion 9 formed in the trough will be formed by placing fillers 25 between vertical wall molds at two or more locations along one side of the trough. These fillers or blocks 25 will 55 be flush with the lower ends of the vertical wall molds such as 7. Therefore, the floor or roof slab 9 at that point will extend to cantilever fashion beyond the adjacent vertical walls. It will be understood, of course, that a sloping shape can be produced by lowering only one mold bottom slab at (Fig. 4) where their edges meet, or by lowering one or both of the remote edges of the trough bottom sections.

In order to reduce the weight of the slab-like portion 9 of the structure, particularly where there are long spans, 65 I will place metal cores in the trough and pour the concrete around them. The cores which may be removable or permanent can conveniently be made of sheet metal. Where insulation is desired, particularly in the floor or roof of a building insulating boards will be placed in the trough-like molds and the concrete poured onto them, thereby bonding the boards to the concrete.

Also, I may integrally cast to the concrete a projection of base board form at the juncture of the concrete wall and floor members, thus eliminating the necessity of later applying wood or tile base boards. Also, this base board shape of the casting may be entirely formed on the side wall a short distance above the floor, thus leaving a space beneath it for insertion of a carpet edge.

I claim as my invention:

1. Molding apparatus for making concrete roof or floor building members having relatively spaced vertical walls integrally cast to said members, that comprises a lower horizontal mold which has a bottom and side walls, vertical wall molds open at their upper and lower ends disposed crosswise of the side walls and mounted for adjustment along the upper edges thereof.

2. Apparatus as recited in claim 1, wherein, partial covers for the lower mold are positioned against the lower face portions of the vertical wall molds.

3. Apparatus as recited in claim 2 wherein, the said covers are hingedly connected to the vertical wall molds.

4. Apparatus as recited in claim 1, wherein, the sides of the lower mold have longitudinally spaced holes and the vertical walls are in pairs and the lower ends of each pair of vertical wall molds have matching holes to receive bolts that extend into certain of first named holes.

5. Apparatus as recited in claim 4 wherein, the side walls for each vertical mold are relatively adjustable in increments equal to the spacing of the said holes in the sides of the lower mold.

6. Apparatus as recited in claim 1, wherein, the lower mold comprises longitudinally aligned sections, the adjacent ends of two sections being vertically adjustable relative to their remote ends, whereby the lower mold may be positioned in two relatively sloping planes.

7. Apparatus as recited in claim 1, wherein a filler block is vertically positioned in one end of the space between two wall molds that form a cavity for one of said vertical walls, the filler extending from the upper end of the cavity to the uppermost plane of the said lower mold.
